CLAIM

The ornamental design for a display screen or portion thereof with graphical user interface, as shown and described.

DESCRIPTION

The sole FIGURE is a front view of a display screen or portion thereof with graphical user interface, showing our new design.

The dotted broken lines illustrate boundaries of the display screen or portion thereof and form no part of the claimed design.

The remaining broken lines, including those depicting text and graphic elements, illustrate portions of the display screen or portion of the graphical user interface that form no part of the claimed design.

1 Claim, 1 Drawing Sheet
